WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

TUBE FRAME.

Application filed March 6, 1922. Serial No. 541,321.

This invention is intended to overcome certain difficulties that are commonly experienced in the use of tube frames in looms for weaving carpets or other pile fabrics in which tufts of yarn are automatically inserted between the warp and filling elements of the fabric during the weaving operation.

As is well known, the individual tuft tubes which form hollow guides or needles for inserting the individual tufts of yarn between the warp elements must be kept in perfect alignment and position, and yet should be capable of permitting quick and convenient removal and replacement of any tube that may be injured, since the loom must stand idle until a perfect tube is substituted for one that is bent or broken.

From the necessities of the case, those tubes must be made of light thin stock and yet must be so supported as to be held firmly in position against accidental displacement. Much loss of time and much trouble is occasioned by insecure and unreliable methods of supporting the tubes on their carrier bars and by similarly defective arrangements for supporting the carrier bar itself.

The present invention deals with the problems by providing a simply constructed and reliable means of attaching and holding the individual tubes in perfect parallelism against accidental displacement, while at the same time any tube can be instantly removed and a new one substituted without appreciable loss of time, and further provides a reliable and secure means of securing the tuft tube carrier bar, which is the backbone of the tube frame, to its supporting brackets by a firm and rigid connection while still preserving the necessary lightness and rigidity of the whole structure.

These and other features of the invention will be explained in the following specification and will be defined in the claims hereto annexed.

In the accompanying drawings I have illustrated some of the preferred arrangements and constructions embodying the principles of this invention, in which: Figure 1 is a plan view of a complete tube frame and tuft-carrying spool with the tubes in their horizontal position, the middle portion of the spool and frame being broken away.

Figure 2 is a perspective view of one end portion of the same.

Figure 3 is a detail view in transverse section of one end of the carrier bar.

Figure 4 is a cross sectional view of the carrier bar and the tube-attaching means taken on a plane between two adjacent tubes.

Figure 5 is a similar view showing an arrangement to prevent chafing the yarn.

Figure 6 is a similar view showing a modified form of chafing-prevention means.

Figure 7 is a perspective view of the tube spacing and holding member of the form shown in the above described figures.

Figure 8 is a longitudinal sectional view across an individual tube showing the notches or indentations for interlocking the tube with its holding member.

Figure 9 is a side elevation of the tube shown in Figure 8.

Figure 10 is a cross section of such tube.

Figures 11 and 12 show slightly modified forms of individual tubes in cross-section and elevation respectively, in which the engaging or interlocking notch is in the form of a slot perforating one side of the tube.

Figure 13 shows in perspective one of the tuft tubes interlocked with a modified form of combined holder and carrier bar made in a single piece.

Figure 14 is a cross section showing the tuft tube holder secured to a hollow metallic carrier bar.

In considering the means by which the individual tuft tubes are firmly supported in proper relationship so as to render them individually replaceable, there are two characteristic novel features in the arrangement to be described one of them relating to the means by which the tuft tubes are so supported, while the other relates to the construction of the individual tuft tubes themselves, both features of course being coordinated in proper relationship to each other.

For the sake of clearness, the front of the tube frame will be regarded as located along the delivery or discharge ends of the row of tuft tubes, while the rear of the frame will be that portion lying toward the spool or in the direction of the intake ends of the row of tubes.

As shown in Figures 1 and 2, the tube frame comprises a longitudinal carrier mem-

auxiliary resistances 10, 10', etc., and several switches 11, 11', etc., for these resistances. A necessary condition in this case is that the electro-magnets 13, 13', etc., controlling the switches should be regulated in such manner as to act successively and at the desired time.

Fig. 2 shows for the coils of these electro-magnets 13, 13', etc., independent circuits arranged in shunt with the terminals of the resistance 3, but these coils could quite well be arranged also in series in a single circuit arranged in shunt with the terminals of this same resistance 3.

Fig. 3 shows a variation of the preceding arrangement in which one of the groups (resistance 10' and switch 11') is branched to the terminals of the field winding 2, in lieu of being branched to the terminals of the resistance 3.

In this case the order of the operations of closing and opening the switches 11, 11', should be determined in such manner that when the speed of the dynamo increases, the switch 11 first opens and the switch 11' closes later; when the speed of the dynamo falls the switch 11' should open first and the switch 11 close later.

In all cases there should be utilized the voltage at the terminals of the field winding itself to cause the operation of the switches 11, 11', etc., and it would be sufficient to change the direction of action of the springs and of the electro-magnets of these switches.

As indicated in Fig. 4, it may even be advantageous to branch the electro-magnet 13 of the switch 11 to the terminals of the resistance 3 and the electro-magnet 13' of the switch 11' to the terminals of the field magnets.

Fig. 5 shows another variant of the particular arrangement forming the subject of the present invention. In this variant a resistance 16 in series with the resistance 3, (and consequently with the field winding 2) may be short-circuited or put in circuit by the automatic switch 11. The circuit of the coil 13 and of its resistance 15 is branched in shunt to the terminals of both of the resistances 3, 16, in series with the field winding 2.

The operation of the device in the arrangement referred to will be easily followed, having regard to the explanations given in connection with the arrangement shown in Fig. 1.

For dynamos of a certain power there may be used two or more than two resist-

ances 16, 16', etc., (see Fig. 6) and as many corresponding switches 11, 11', with the double condition of exciting each of the electro-magnets of these switches by means of a coil under the influence of the difference in potential between the terminals of the whole of the resistances 3, 16, 16' etc., in series with the field winding 2 and by regulating the switches in such manner that they act successively and at the desired times.

The coils of the electro-magnets 13, 13', etc., may also be each arranged in an independent circuit or all put in series in a single circuit branched to the terminals of the whole of the resistances 13, 16, 16' etc. Fig. 6 illustrates an example of the latter arrangement.

Having now particularly described and ascertained the nature of my said invention and in what manner the same is to be performed, I declare that what I claim is:

1. Means for regulating the voltage of dynamos of variable speed and variable load, with vibrating regulators having two contacts, comprising in combination with a dynamo having a field winding and a resistance in series with the field winding, a second resistance branched in parallel with said first resistance, an electro-magnetic automatic switch in the connection between the second resistance and the field winding, the magnet of said switch having its terminals connected to the terminals of the first named resistance, whereby said magnet is under the influence of the difference of potential at the terminals of the resistance in the field winding.

2. Means for regulating the voltage of dynamos of variable speed and variable load, with vibrating regulators having two contacts, comprising in combination with a dynamo having a field winding and a resistance in series with the field winding, a second resistance branched in parallel with said field winding, an electro-magnetic automatic switch in the connection between the second resistance and the field winding, the magnet of said switch having its terminals connected to the terminals of one of the elements of the field winding, whereby said magnet is under the influence of the difference of potential at the terminals of said element.

In witness whereof I have hereunto set my hand.

HENRI BÉNIT.

5 a pair of aligned slots in said holding members and having detachable interlocking engagement with one of the holding members to prevent accidental displacement in an axial direction, substantially as described.

10 2. In a tube frame, the combination of a carrier bar provided with two slotted holding members extending in parallelism longitudinally of the bar and projecting laterally from the bar to afford forward and rear supporting means for spacing and holding a series of tuft tubes at equally spaced intervals intermediate of their ends by 15 means of the tube engaging inside edges of the slots in said holding members, and means for detachably locking the tubes therein against axial displacement, substantially as described.

20 3. In a tube frame, the combination of a longitudinal carrier bar, two parallel apertured holding members projecting laterally therefrom, one in advance of the other and extending lengthwise of the carrier bar, a series of separate tuft tubes each mounted in corresponding apertures in said holding members and detachably locked against axial movement therein, substantially as described.

30 4. In a tube frame, the combination of a longitudinal carrier bar, tube retaining means projecting laterally therefrom to surround and support in spaced relation a series of tuft tubes by external engagement 35 with each individual tube at its middle and at its rear portions respectively, each tube being detachably held in operative position to permit its separate removal, substantially as described.

40 5. In a tube frame, the combination of a carrier bar, longitudinal parallel holding members each provided with a series of tube surrounded apertures, registering with those in the other holding member in the 45 axial direction of the tubes, a series of tuft tubes inserted through said apertures and detachably held therein so as to permit removal of any tube without disturbing other tubes, substantially as described.

50 6. In a tube frame, the combination of a longitudinal carrier bar provided with tube supporting and spacing members, a series of 55 separate tuft tubes each provided with a locking notch formed in its side wall intermediate of its ends to engage and detachably interlock with the said holding members to prevent axial displacement while permitting the separate removal of any individual tube without disturbing others, substantially as described.

60 7. In a tube frame, the combination of a longitudinal carrier bar, tube holding means projecting laterally therefrom so as to surround and supportingly engage each individual tube at different portions of its

length, a series of tuft tubes provided intermediate of their ends with notches adapted to interlock with said holding means to prevent axial displacement and permit separate removal of any tube, substantially as 70 described.

8. A self-locking tuft tube for a tube frame, embracing a tubular tuft guide of flattened cross-section whose side wall is provided with a notch adapted to engage an 75 external holding member to prevent axial displacement, substantially as described.

9. A self-locking tuft tube for a tube frame, embracing in its construction a tube of spring metal one of whose side walls is 80 provided with a notch cooperatively arranged to yieldingly engage the edge of an external holding member, to be detachably locked against axial displacement, substantially as described.

10. In a tube frame for weaving, the combination of a carrier bar, tube holding means for securing a series of mechanically detachable tuft tubes in parallelism transversely of the bar, and a guard member extending beneath the intake ends of the tubes and formed to project outwardly beyond the adjacent end edges of the tube to guide the yarn entering the tube out of contact with said end edges while permitting 95 the removal of individual tuft tubes, substantially as described.

11. In a tube frame for weaving, the combination of a carrier-bar, a longitudinal tube-holding member secured against the front of said carrier-bar, a series of tuft tubes detachably inserted in said holding member across the front of the bar, and a transversely bowed longitudinal anti-chafing member detachably secured between the 100 front face of the bar and the rear ends of the tubes so as to deflect the yarn entering the tuft tubes from the rear end edges of the tubes, substantially as described.

12. A tuft tube guide for delivering a 110 yarn tuft to the fabric being woven open at its ends to permit the feeding of the yarn through it and having a side wall provided intermediate of said end openings with means for locking it detachably to its holding member, substantially as described.

13. In a tube frame for weaving the combination of a longitudinal carrier bar, a longitudinal tube carrying member secured to the carrier bar and having its forward and rearward edges outwardly turned away from the bar to form parallel tube holding ledges and a series of tubes detachably inserted in said ledges to lie transversely thereof in parallelism with one another, substantially as described.

14. A suspension hanger for supporting the yarn-spool and the tube-carrying bar of a tube frame in operative relationship, embracing a vertical arm provided with spool- 130

supporting and chain-engaging members and having at its lower end laterally projecting individually yielding attaching members angularly disposed to one another and arranged to form a contractible box in lapped engagement with corresponding faces of the carrier bar to prevent displacement between the carrier bar and the hanger

transversely of the carrier bar and adapted to receive clamping screws in order to be firmly secured to said carrier bar, substantially as described. 10

In witness whereof, I have subscribed the above specification.

WALTER BIXBY.
